HIGH FREQUENCY AMPLIFIER AND CIRCUIT THEREFOR

Arne Zillger, Narberth, Pa., assignor to National Television Corporation, Wilmington, Del., a corporation of Delaware

Application September 13, 1933, Serial No. 689,256

4 Claims. (Cl. 179—171)

This invention relates to amplifiers for high frequency electrical oscillations such as are used in television apparatus where pictures are scanned in successive lines.

In sending a television picture composed of successively scanned picture lines it is necessary to expose a light-sensitive cell very rapidly to successive portions of the picture and to amplify the feeble impulses produced by the cell so that they are strong enough to broadcast over the air or to send over wires to the receiving apparatus. The receiving apparatus picks up the impulses thus sent out and again amplifies them sufficiently to operate a modulating lamp, the light of which is caused by a suitable scanning device to illuminate successive points of the received picture image.

In order to produce a picture with fair detail relatively high frequencies are necessary. Thus a picture having 60 lines with 72 picture elements on a line and transmitted at the rate of 20 pictures per second has 86,400 picture elements per second and the signal may have a possible frequency of 43,200 cycles per second. Where a greater number of lines is used in the picture, and a greater number of picture elements per line, and a greater number of pictures per second, the frequency may rise to a much greater figure than this, perhaps, in the neighborhood of 200,000 cycles per second. The average radio receiver for sound reproduction amplifies a frequency in the neighborhood of 10,000 cycles per second and cannot go much higher. This frequency appears to be sufficient in the audible range and hence there has been little effort made to design amplifiers for the higher frequencies. By means of resistance coupled amplifiers a higher frequency can be had but there is usually a distortion caused by unequal passing of high and low frequencies with high impedance in the output circuit preventing the transmission of the impulses over wires for any appreciable distance. Transformer coupled amplifiers have heretofore completely cut off the high frequencies above say 10,000 cycles, and have a tendency to pass certain frequencies better than others.

It is one of the objects of the present invention to provide an amplifier which will pass without distortion frequencies in the neighborhood of 200,000 cycles or higher.

Another object of the invention is to provide an amplifier for high frequency oscillation which has a low output impedance so that signals from the amplifier may be sent relatively long distance over wires.

Still another object of the invention is the provision of a high frequency amplifier in which the high potential circuits and those which are highly sensitive are separated from the low potential circuits and capacity between them is reduced to a minimum.

Another object of the invention is to provide an amplifier tube in which the input capacity is reduced to a minimum as well as the grid-plate capacity.

A still further object of the invention is to provide a push-pull amplifier tube for use with high frequency circuits in which the capacities between the grids and plates and between the grids and cathodes are reduced to a minimum.

Still another object of the invention is to provide a means for mounting standard tubes in a high frequency amplifier so as to maintain at a minimum the capacitive effect between the grids, plates, and cathodes of the tubes.

A still further object of the invention is to provide a high power output tube for a high frequency amplifier with minimum capacity between the elements.

Other objects and objects relating to particular arrangements of the circuit and specific constructions of various parts for carrying out the purposes of the invention will be apparent as the description thereof proceeds.

The invention has been illustrated in the accompanying drawings in which:

Fig. 1 is a partly diagrammatic perspective view of an amplifier constructed in accordance with my improved design;

Fig. 2 is a circuit diagram of a portion of the amplifier shown in Fig. 1;

Fig. 3 is a circuit diagram of a modified form of output tube to be used with a different type of modulating lamp;

Fig. 4 is a perspective view partly in section of a special type of amplifier tube which may be used with the amplifier of the invention;

Fig. 5 is a sectional front elevational view of one form of power output tube which may be used with the invention;

Fig. 6 is a sectional side elevational view of the elements shown in Fig. 5;

Fig. 7 is a plan view of the elements shown in Fig. 6;

Fig. 8 is a sectional plan view taken on the line 8—8 of Fig. 5 showing a means of supporting the elements;

Fig. 9 is a perspective view of a portion of a lamp showing a modified filament construction;

Fig. 10 is a perspective view partly in section of a push-pull amplifier tube;

Fig. 11 is a sectional front view through one set of elements of the tube of Fig. 10; and

Fig. 12 is a sectional side elevational view showing the mounting of the lower ends of the elements.

In general the invention comprises maintaining a separate and distinct level for all of the high potential circuits in the amplifier and another level for the low potential circuits, and providing certain specially constructed tubes and other parts which will be hereinafter described.

In Fig. 1 is shown an amplifier having two stages of so-called radio frequency amplification, a detector stage, and three stages of transformer coupled amplification. The circuit comprises an antenna coil 1 having a primary coil 2 one end of which is connected to the antenna 3 while the other is connected to ground at 4. The coil 1 has a secondary winding 5 which is connected at one end to one side of a variable condenser 6 and to the grid post 7 of a special amplifying tube 8, while the other end of the coil 2 is connected to the rotor of the condenser 6 and to ground at 9.

The tube 8 has a grid post 7 mounted on the glass bulb at the top, as indicated, and at the opposite side of the bulb is provided a plate connecting post 10 mounted in a similar manner. The base 11 of the tube is provided with the usual terminals so that it fits into a standard socket 12 having two heater terminals 13, a cathode terminal 14, and a screen grid terminal 15. The cathode terminal 14 is connected through a resistance 16 which has a by-pass condenser 17 to a ground wire 18 grounded at 19. This maintains the cathode at a higher potential than ground and is done to give the grid a negative bias, as is well known. The resistance 16 may be made variable as one means of controlling the volume of the amplifier. Any other type of volume control may of course be used. The heater terminals 13 are connected by means of a twisted pair of wires 20 which lead to a secondary 21 on a transformer 22 the primary 23 of which is connected to the alternating power line as indicated by the generator 24. The secondary 21 has its midpoint grounded as at 21a. The screen grid terminal 15 is connected to a wire 25 which is given a positive potential at 25a. A by-pass condenser 26 is connected between the terminal 15 and a ground connection at 27, the condenser being positioned in close proximity to the screen grid connection. The plate terminal 10 of the tube is connected to the primary winding 28 of the coil 29 which has its other end connected by means of the wire 30 to the positive side of a B battery (not shown but designated "B+") or to any other source of plate potential supply.

The coil 29 has a secondary winding 31 one end of which is connected to the variable condenser 32 and to the grid post 33 of the second amplifier tube 34, while the other end is connected to the rotor of the condenser 32 and to the grounded wire 18 by means of the wire 35. The tube 34 is similar to the tube 8 and is mounted on a similar socket 36 which has a cathode terminal 37 connected through a resistance 38 and by-pass condenser 39 to the grounded wire 18. The heater terminals 40 on the socket 36 are connected by means of the twisted wires 41 to the heater supply secondary 21 of the transformer 22. The screen grid connection 42

is connected to the wire 25 which provides the potential of the screen grid as described in connection with the last tube. A condenser 26a is placed in close proximity to the screen grid connection 42 and is connected to it and to ground at 27a.

While the twisted wires for the heater supply have been shown rather long on the tubes 8 and 34 and also on the succeeding tubes, it will be understood that this has been done for purposes of illustration only and that these connections are actually made as short as possible to reduce any tendency to pick up the sixty cycle hum by the other wires of the circuit.

The tube 34 has a plate terminal 43 mounted on the bulb similar to the plate terminal 10 of the tube 8, and this terminal is connected to a primary winding 44 of the coil 45. The other end of the winding is connected by means of the wire 46 to the plate potential supply as indicated by B+. The coil 45 is provided with a secondary 47 which has one end connected to the variable condenser 48 and also through a grid leak and condenser 49 to the grid terminal 50 of the detector tube 51. The other end of the secondary 47 is connected to the rotor of the condenser 48 and by means of the wire 52 to the ground wire 18.

The special detector tube 51 is mounted upon a standard base 53 having a cathode connection 54 and two heater connectors 55. The cathode connector 54 is connected directly to the grounded wire 18 by means of the wire 56. The terminals 55 for the heater are shown connected by means of the twisted wires 57 to the heater supply transformer 22 as indicated.

The detector tube 51 feeds into a transformer 58 which is specially wound to pass high frequencies. This transformer forms no part of the present invention but has been developed by 40 Wired Radio Inc., of Ampere, New Jersey. The detector tube 51 has a plate terminal 59 mounted on the bulb similar to the tubes 8 and 34 which connects by means of a wire 60 to a terminal 61 on the top of the transformer which is connected to one end of the primary coil (not shown). The other end of the primary coil has a terminal 62 arranged at the lower end of the transformer and this terminal is connected through a balancing resistance 63 by means of the wire 64 to a positive plate potential as indicated at B+.

The transformer 58 to be described is the first of a series of push-pull transformers and the secondary of this transformer has a midpoint connection brought out at the terminal 65 at the lower end thereof which is connected by means of the wire 66 to the common ground wire 18. The two ends of the secondary of the transformer 58 are provided with terminals 67 and 68 at the top of the transformer and these are connected respectively by means of short wires 69 and 70 to the grid terminals 71 and 72 of the special push-pull amplifying tube 73 which is to be hereinafter more specifically described.

The tube 73 is mounted on a base 74 which fits into a standard socket 75 having at least three terminals, a cathode terminal 76 and two heater terminals 77. The cathode terminal 76 may be connected through a resistance and by-pass condenser 78 to the grounded wire 18. The two heater leads 77 are connected by twisted wires 79 to the power supply circuit at the transformer secondary 21. The push-pull tube 73 is provided with two plate connectors 80 and 81 which may

be connected by means of wires 82 and 83 respectively to plate terminals 84 and 85 on the second push-pull transformer 86. These terminals are at the top of the transformer and are connected to the ends of the primary coil thereof which in turn has a midpoint connection provided with a terminal 87 at the lower end of the transformer which may be connected by means of the wire 88 to a plate potential indicated at 10 B+.

The transformer 86 is provided with a secondary coil having end terminals 89 and 90 at the top thereof which may be connected respectively by short wires 90a and 91 to the grid terminals 92 and 93 of the second push-pull amplifying tube 94 which is made exactly similar to the first tube. The midpoint of the secondary of the transformer 86 is brought out through a terminal 89a and connected directly to the grounded wire 18. The tube 94 is provided with a socket 95 having heater leads 96 connected by means of the twisted wire 97 to the power supply and a cathode terminal 98 connected through a resistance 99 and by-pass condenser to the grounded wire 18.

Two plate terminals 100 and 101 are provided on the top of the tube 94. These may be connected respectively by means of wires 102 and 103 to the primary end terminals 104 and 105 on the top of the push-pull transformer 106. The midpoint terminal 107 of this primary is provided at the bottom of the transformer and may be connected by means of the wire 108 to a plate potential indicated by B+. The transformer 106 is also provided with a secondary 35 having end terminals 109 and 110 which may be connected respectively by means of the wires 111 and 112 to grid terminals 113 and 114 on the push-pull tube 115. The midpoint of the secondary is brought out by terminal 109a at the 40 bottom of the transformer and connected to the grounded lead 18.

The tube 115 is preferably a power output tube and does not, therefore, need an independently heated cathode. Hence no cathode terminal 45 need be provided on the socket 116 for the tube but heater terminals 117 are provided which may be independently connected by the twisted wires 118 to the secondary 119 of the transformer 22 for giving the tube 115, which corresponds to 50 the 45 type tube, a different filament voltage than the preceding tubes. The secondary 119 may have its center point connected to ground at 120 through a resistance 121 provided with a by-pass condenser 122. This maintains the filament 55 of the tube 115 at a higher potential than ground thus properly biasing the grid.

The output tube 115 is provided with two plate terminals 123 and 124 which may be connected by means of the leads 125 and 126 to a coupling 60 transformer 127. This transformer has a pair of primary terminals 128 and 129 to which are connected the leads 125 and 126, and the midpoint of the primary is brought out through a terminal 130 which may be connected by means 65 of a wire 131 to a positive plate potential indicated at B+. The ends of the secondary of the transformer 127 are provided with terminals 132 and 133 which may be connected respectively by wires 134 and 135 to a neon glow lamp 136 the plate of which may be scanned by suitable means 70 for producing a television picture in accordance with the incoming impulses of the amplifier.

Grid leak and condenser rectification has been shown for purposes of illustration in connection 75 with this circuit but it will be understood that

other types may be used such as plate rectification. Also other grid biasing means may be used if desired.

In Fig. 2 is shown the circuit diagram corresponding to the amplifier of Fig. 1 from the detector tube 51 on. Here the tubes 73, 94, and 115 are indicated as containing two separate sets of elements. Thus the tube 73 has two grids 137 and 138 connected to the grid terminals 71 and 72 respectively on the outside of the bulb, two plates 139 and 140 connected respectively to the external plate terminals 80 and 81 on the outside of the tube, two cathodes 141 and 142 connected together inside of the tube and to the external cathode terminal 76, and a pair of heaters 143 and 144 connected in parallel and to the heater terminals 77.

The tube 94 is exactly similar to the tube 73 and need not be further described in connection with this figure.

The tube 115 is a power output tube with two sets of elements. Thus a pair of grids 145 and 146 are connected respectively to the external grid terminals 113 and 114, while the anodes 147 and 148 are connected to the external plate terminals 123 and 124 respectively. Between the grid 145 and plate 147 is the filament 149, while the filament 150 is between the grid 146 and the plate 148. These filaments are connected in parallel to the filament terminals 117 at the base 30 of the tube.

From this construction as illustrated in these two figures it will be evident that a push-pull circuit is provided in which the usual two amplifying tubes for amplifying each side of the circuit 35 in one stage are included in one envelope, thus facilitating the construction of the amplifier and the positioning of the unit so as to keep the high potential circuit separated from the low potential circuit. The manner of constructing these tubes 40 will be more specifically described later.

Attention is drawn to the resistance 63 in series with the primary of the transformer 58. This resistance is inserted to balance the impedance between the plate and cathode of the detector 45 tube so that the high frequency side of the transformer is balanced with the low frequency side thus preventing distortion in the high frequency current. The placing of this resistance forms no part of the present invention but is 50 described and claimed in my prior filed application Serial No. 682,209, filed July 26, 1933, entitled "Balanced amplifier circuit".

The amplifier as described above may be used with a plate type neon lamp as indicated at 55 136 but I may prefer to use a different type of lamp having a much higher current consumption. Such a lamp, illustrated in Fig. 3 is shown and described in Patent No. 2,089,806 to John W. McKay. Such a lamp is constructed of two 60 bulbs 151 and 152 spaced apart from each other and connected by a glass tube 153. The bulb 152 contains the anode and the bulb 151 contains the cathode, and a terminal 154 is mounted on the bulb 152 for the anode while a terminal 155 on the bulb 151 is connected to the cathode.

In order to operate such a lamp it may be necessary to use several output tubes in parallel. In one instance I found it necessary to 70 use three of the 45 type tubes in parallel, but connecting these tubes in the ordinary manner necessitates a number of wires between the grid connections and between the plate connections which cause considerable capacity not only be- 75

tween them but to ground and to the filament leads. A feature of the invention, therefore, is the overcoming of this defect by the construction of a tube which contains all of the output tubes necessary in one envelope.

This tube is shown diagrammatically in Fig. 3 where the envelope 156 contains the three sets of filaments 157, 158, and 159, the three plates 160, 161, and 162 connected together, and the three grids 163, 164, and 165 also connected together. The grid and plate leads are so constructed as to minimize the capacity effect as will be described later, it being sufficient to point out at this time that the grids are connected by means of a wire 166 to the grid terminal 109 of the transformer 106 while the other end 110 of the secondary of the transformer is connected to ground by means of the wire 167. The mid-point of the secondary 109^a in Fig. 2 is not used in this case. The plates of the tube are connected by means of a wire 168 to the cathode terminal 155 of the lamp while the anode terminal 154 thereof is connected to a positive potential indicated at B+.

In Fig. 4 I have shown one type of amplifier tube which may be used for the radio frequency amplifiers in the circuit of Fig. 1. This tube may be similar in characteristics to the 56 type tube but certain changes have been made to eliminate capacity effects between the plate, grid, and cathode. As shown the tube comprises an envelope 169 supported upon a base 170 which carries the various terminals for making the connections to the tube. The tube is provided with an internally extending press 171 which has integrally formed upstanding glass legs 172 on the ends thereof in which are sealed the plate support rods 173. Upon these support rods is mounted the whole element assembly.

For such a mounting the anode is constructed of a pair of metal plates 174 stamped out with a semi-cylindrical portion 175 extending through the center thereof. These plates are attached together in such a manner that the semi-cylindrical portions 175 form a cylindrical plate or anode, and suitable curved portions 176 at the edges of the plates fit over the plate support rods 173. At each end of the anode construction is placed a mica plate 177 with holes 178 to receive the anode support rods, a central hole 179 to receive the tubular cathode 180, and on either side of the hole 179 another hole 181 to receive the grid posts 182. Thus the grid and cathode are supported with respect to the anode.

An insulated filamentary heater wire 183 extends in the form of a loop or hairpin through the tubular cathode and has its ends attached to the support rods 184 in the press 171. Lead-in wires 185 connect the filament support rods with the two heater prongs 186 on the base 170. The tubular cathode may be held longitudinally in place by a strip 187 which surrounds the lower end thereof and this strip may be welded to a support rod 188 sealed in the center of the press 171. A lead-in wire 189 from the rod 188 may be connected to the cathode prong 190 on the base 170. The other two prongs on the base (if it is to fit into a standard five prong socket) are not used.

One of the plate support rods 173 at the top is connected by means of a wire 191 to a metal cap 192 attached to the outside of the bulb at one side of the top thereof, the wire being fused or sealed through an opening in the glass in the manner of making the grid connection on a

shield grid tube. In like manner one of the grid support rods 182 may be connected by means of the wire 193 to a cap 194 mounted on the opposite side of the top of the bulb. The wires 191 and 193 are given a slight sinuous curve in order to permit small movements of the element structure within the bulb due to temperature changes and thus to eliminate any strain on the seals where the wires pass through the envelope. The wires are made as straight as possible, all coils being avoided, and are positioned as far away from any other parts of the tube as is possible, thus avoiding any capacity relation. With this construction the high frequency plate and grid connections are separated from each other and from the other parts of the tube, especially the low potential circuits.

While this tube is shown as a simple 56 type it will be evident that a shield grid tube may be manufactured in the same manner, there being required an additional lead down to one of the base prongs for the shield grid potential connection. Such a tube with a shield grid is shown as tubes 8 and 34 in Fig. 1, while the detector tube 51 of that figure may be constructed exactly similar to the tube shown in Fig. 4. It will be noted that the plate and grid connections through the press down to the base of the tube are entirely eliminated which removes a large part of the undesirable capacity between these connections in the ordinary tube.

In Fig. 10 is shown a tube similar to that in Fig. 4 but provided with two sets of elements making it a push-pull tube similar to the tubes 73 and 94 of Fig. 1. In this construction the envelope 195 is supported upon a base 196 carrying a plurality of terminals for making the connections to the tube. An inturned press 197 supports the elements and for this purpose is provided with upstanding end posts 198 similar to those shown in the tube of Fig. 4. A pair of support rods 199 are fused into the glass posts 198 and to these are fused on each side a transverse glass bead 200. Into these glass beads are fused the plate support rods 201 and 202 of a pair of element assemblies 203 and 204 which are exactly like the element assembly shown in Fig. 4 and need no specific description here.

The two cathodes 205 and 206, shown best in Fig. 12, are fastened together by the metal strip 207 which is welded to the central support rod 208. A lead-in wire 209 is connected to this support rod and leads to the prong 210 at the base of the tube. The filaments are connected in parallel and for this purpose the end 209 of one filament is connected to a transverse connector 210 as is also the end 211 of the other filament. The connector 210 is attached to a support rod 212 which is sealed in the press 197. In like manner the ends 213 and 214 of the filament are secured to the connector 215 which in turn is attached to the support rod 216 sealed in the press 197. Lead-in wires 217 and 218 may connect the heater rods 212 and 216 respectively with heater prongs 219 and 220 as indicated.

One of the plate support rods 201 is then connected by means of a wire 221 to a cap 222 on the outside surface of the bulb while one of the other plate support rods 202 is connected by means of a wire 223 to a cap 224 also positioned on the outer surface of the bulb at about 45 degrees removed from the other. In the same manner the grid post 225 on the element assembly 203 may be connected by means of a wire 226 to the cap 227 on the outer surface of the bulb about diametri-

cally opposite the plate cap 224 and the grid post 228 of the element assembly 204 may be connected by means of a wire 229 to the cap 230 on the outer surface of the bulb about diametrically opposite to the cap 222.

The tube, of course, is prepared and treated similarly to ordinary vacuum tubes of this nature and may be provided with a getter cup 231 suitably supported by means of the wire 232 on one of the support rods, as for instance, the rod 199.

It will be evident from this construction that the two element groups 203 and 204 are independently positioned in the envelope so that each operates separately as far as the plates and grids are concerned and can therefore be used in push-pull formation. As the cathodes in a push-pull circuit are connected together this connection is made in the tube and therefore avoids the additional wires and their accompanying capacity effect. As in the other tube previously described the grid and plate supports are entirely separated from the other wiring, especially from the wires which usually pass through the press of the tube and the capacity effect caused by such wiring is thus eliminated.

The power output tube 115 of Fig. 1 may be similarly constructed although instead of a separately heated cathode a filamentary cathode may be used. In this case only the heater terminals on the base of the tubes are used while other parts of the wiring would be the same.

In Figs. 5 to 9 inclusive is shown a tube corresponding to the triple element output tube indicated diagrammatically in Fig. 3. This tube has the same characteristics as three 45 type tubes connected in parallel but a large amount of the disadvantages arising from such a hook-up is eliminated. This tube comprises an envelope 233 supported on a base 234 in the usual manner and having an inturned press 235 for supporting the elements. The elements of the tube comprise three independent element assemblies 236, 237, and 238. These element assemblies are exactly the same and it will be deemed therefore only necessary to describe one. The assembly 236 comprises an anode or plate 239 having two complementary parts which when positioned together provide a tubular central portion 240 having substantially rectangular cross-section and two side extending flanges 241 which may be attached to side supporting rods 242. A grid 243 composed of a helix of wire is wound about two support rods 244 which are longer than the plate and extend above and below it. A single sheet of mica 245 is provided across the top of the three element assemblies and a second single sheet 246 of the same material is provided across the bottom. The plate support rods 242 pass through holes provided for them in the mica sheets which tend to rigidly support the element assemblies in spaced relation within the envelope. Also the mica sheets are provided with holes to receive the grid support rods 244 thus maintaining the grids in spaced relation to the anodes.

The element assemblies are mounted inside of the envelope 233 by means of two glass extension supports 247 formed on the press 235. The ends of these glass extensions are bent outwardly and are provided with short rods 248 sealed therein. The plate support rods 242 of the central element assembly are made somewhat longer at the lower end and are welded to the rods 248 thus supporting the whole assembly within the envelope. Transverse rods 249 mounted directly under the

anodes are welded to each of the rods 242, thus making an electrical connection between the three anodes.

A filamentary cathode 250 comprises an M-shaped filament which is supported within the grid 243. The two upper vertexes of the filament are supported on springs 251 which in turn are held by a small glass tube 252 whose ends are supported by short support rods 253 inserted in the ends of the tube and welded to the upper ends of the plate support rods 242. In order to support the lower ends of the filament a glass bead is provided in which two rods 254 and 255 are sealed. These rods extend both above and below the beads and have their upper ends connected to the ends of the filament. A third support rod 256 is sealed in the center of the bead and its upper end terminates in a hook 257 which holds the central V-shaped loop of the M filament. In order to support this glass bead I provide a short support rod 258 in each end of the bead and these rods are then welded to the plate support rods 242 thus rigidly mounting the bead beneath the plate.

One of these beads is mounted beneath each element assembly. A transverse connecting rod 259 is connected to the lower end of each of the rods 254 passing through the three beads, and a second transverse connecting rod 260 is welded to the lower ends of the three rods 255 passing through the three beads. Thus the three filaments are connected in parallel. In order to make the outside connection for the filament I connect the central support rods 254 and 255 to two short support rods 261 and 262 respectively, these support rods being sealed in the press 235 and having lead-in wires 263 and 264 connecting them respectively with heater prongs 265 and 266 at the base of the tube.

As the anodes or plates are all connected together by means of the rods 249 it is necessary only to connect one of the support rods 242, as by means of the wire 267, at the top thereof to a plate terminal 268 mounted like a cap on the outside of the envelope near the top thereof. The grids may all be connected together by means of a transverse rod 269 which may be welded to the upper ends of the grid support rods 244 and this rod may be connected by means of a wire 270 to a grid cap 271 mounted on the outside of the bulb, preferably diametrically opposite the plate terminal 268. The wires 267 and 270 are given a slightly sinuous curve to allow for movement of the elements due to expansion and contraction and to remove any undue strain on the seals where the wires pass through the glass envelope which they necessarily have to do. The mica sheets 245 and 246 are each provided with openings 272, 273, and 274 to permit the mounting of the filaments without interference.

The M filaments 250 shown in Figs. 5, 6, and 7 are connected together at their ends thereof, the vertexes being insulated from each other. Inasmuch, however, as these filaments are connected in parallel it is possible to connect the vertexes together without insulating them and this simplifies the supporting structure. In Fig. 9 this way of mounting the filaments is shown. The filaments 250^a have one end connected to the transverse conducting member 259^a while the other ends are connected to the transverse conductor 260^a. The conductors 250^a and 260^a are connected respectively to support rods 261^a and 262^a which are sealed in the press 235^a. The lower vertexes of the filaments are supported on

hooks 257^a which are in turn welded to a transverse connector 256^a which is supported upon a central support rod 258^a also sealed in the press. The right hand upper vertexes of the three filaments seen in Fig. 9 are supported on springs 251^a suspended from a rod 252^a having its ends sealed in separated glass beads 253^a. A second support rod 254^a is mounted between the beads 253^a parallel to the rod 252^a and supports the left hand upper vertexes 250^a by means of the coil springs 255^a. The beads may be supported by wire loops 263^a which may be attached to the anode support rods 242 above the mica plate 245.

This construction simplifies the supporting of the filaments and has an advantage in the operation of the tube, for if one filament should burn out at one point, current would still flow through the other three-quarters of the filament, and that element assembly would not be completely incapacitated.

From the above description it will be evident that the three element assemblies 236, 237 and 238 are connected in parallel, the plates being connected together, the grids being connected together, and the filaments being connected together. These connections, however, are made in the tube with a minimum of wiring so that the capacity between various elements is reduced to an absolute minimum.

The above description has been directed to an amplifier for high frequency oscillations in which specially designed tubes have been used. It is evident, however, that it is possible to use standard tubes in a high frequency circuit by following as nearly as possible the principles already outlined, although naturally the results will not be as good.

While the invention has been described with a certain type of amplifier and using certain types of tubes the invention may be adapted to any system of amplification which will be greatly improved for high frequencies by maintaining the high potential and highly sensitive circuits on one level and the low potential circuits on another. Also the special tubes described are not to be limited to any particular type as any tube from triodes up to the more complicated pentodes may be adapted for this type of circuit with equally good results. I do not, therefore, desire to limit any part of the invention to what is shown and described except as such limitations are contained in the appended claims.

What I desire to secure and claim by Letters Patent is:

1. A high frequency amplifier comprising a plurality of amplifier tubes coupled together by transformers, terminals for the grid and plate connections at spaced points on the tops of said tubes, grid and plate terminals on said trans-

formers, and means to position said transformers with respect to said tubes so that said terminals are at substantially the same level as the tube terminals whereby the length of the connection from the grids and plates of the tubes to the 5 transformers may be reduced to a minimum and they may be separated from the other connections for the tubes and transformers.

2. A high frequency amplifier comprising a plurality of amplifying tubes, each of said tubes 10 having a press, a grid, a plate spaced from said grid, a cathode spaced from said grid, means to support said plate, grid, and cathode on said press, connections for said cathode extending through said press, a connector for said grid 15 mounted on the top of said envelope, a connector for said plate mounted on the top of said envelope and spaced from said grid connector, a plurality of transformers capable of passing high frequencies, said transformers having grid connectors and plate connectors, and means to mount said transformers in close proximity to said tubes with said plate connectors and said grid connectors about approximately the same level as said plate and grid connectors on said tubes. 20

3. An amplifier for high frequency oscillations comprising a plurality of amplifying tubes, each of said tubes having grid and plate terminals provided at one end of the tube spaced from the other terminals for said tube, coupling units between said tubes, said coupling units being substantially as large as the tubes and having the terminals for the plate terminal of one tube and the grid terminal of the next positioned at one end of the unit while the other terminals are 30 positioned at the opposite end of the unit, and means to position said tubes and coupling units so that the connections between the grid and plate terminals of said tubes and said units are maintained substantially at the level of the top 35 of said tubes.

4. A high frequency amplifier comprising a plurality of amplifying tubes each of said tubes having a press, a grid, a plate spaced from said grid, a cathode spaced from said grid, means to support said plate, grid and cathode on said press, connections for said cathode extending through said press, a connector for said grid 45 mounted on the top of said envelope, a connector for said plate mounted on the top of said envelope and spaced from said grid connector, a plurality of coupling devices capable of passing high frequencies, said devices having grid connectors and plate connectors, and means to mount said devices in close proximity to said tubes with said plate connectors and said grid connectors substantially at the same level as said grid and plate connectors on said tubes. 50

ARNO ZILLGER.
